DEVICE FOR APPLYING PAPER BAGS TO
GARMENTSCharles F. Wells and William O. Purkins,
Temple, Tex.

Application December 2, 1935, Serial No. 52,609

2 Claims. (Cl. 226—18)

This invention is a device for applying paper bags to garments, and the object of the invention is to provide a device of this character especially designed for use in cleaning, pressing and tailoring establishments to facilitate the placing of a pressed garment in a bag or wrapper of the type now usually used by such business concerns in delivering garments to the customers.

10 Among the objects of the invention are to provide a device of this character characterized by simplicity of construction, facility of operation and practicability.

The invention together with its objects and advantages will be best understood from a study of the following description taken in connection with the accompanying drawings wherein:

Figure 1 is a view mostly in elevation of the device certain parts being shown in section.

20 Figure 2 is a top plan view of the device.

Figure 3 is a horizontal sectional view taken near the lower end of the device.

Figure 4 is a perspective view of a vertically movable rod.

25 Figure 5 is a perspective view of a guide rod.

Figure 6 is a perspective view of a sleeve and

Figure 7 is an end elevational view of one of the handle equipped arms of the device.

Referring to the drawings by reference numerals it will be seen that the device comprises a base consisting of a pair of opposed spaced parallel members 5—5 provided with apertured flanges or otherwise as at 6 for securing the members 5 to a floor or the like.

35 Supported between the members 5 and clamped thereto through the medium of suitable clamps 7 is a cross member 8 having upturned ends 9 and 10 respectively. Secured to the end 9 of the member 8 is a tubular standard or post 11 in the upper end of which is journalled a shank 12. Inward movement of the shank 12 is limited by a suitable collar 13.

Extending, or branching from the shank 12 are arms 14 that have horizontal portions 14a provided at their outer ends with depending handles 15. The handles 15 are secured to the arm extension 14a in any suitable manner, preferably by being integral therewith.

40 Adjacent the handle equipped end thereof each arm extension 14a is provided with a double suspension hook indicated generally by the reference numeral 16.

45 As best shown in Figure 7 each hook 16 is formed from a single length of wire or the like bent in a substantially inverted U, and the legs

of the U then reversely bent to provide hooks disposed at opposite sides of the member 14a. At the closed end of the U the hook 16 is welded or otherwise secured to the arm extension 14a.

The hooks 16 serve to removably support horizontal bars 17. As best shown in Figure 2 the bars 17 are arranged substantially in the form of a triangle with the ends of the bars engaging in the hooks of the members 16.

5 Each bar 17 is adapted to support thereon a plurality of superimposed bags 18 which are folded over the respective bars 17 in the manner clearly suggested in broken line in Figure 1. The bags 18 are of the type usually provided for covering pressed and cleaned garments by a tailoring establishment.

The device further includes an elevator indicated generally by the reference numeral 20.

The elevator 20 comprises an elongated tube 21 having a threaded end 21a that is screwed into the end 10 of the member 8. Arranged for vertical sliding movement within the member 21 is a rod 22 that is provided on its upper end with a hook 23 with which is adapted to be engaged the hook of a conventional garment hanger.

20 Disposed over the member 21 is a cover sleeve 24 of any suitable, preferably transparent material. The member 24 at one end is provided with a collar 25 through the medium of which 30 and a set screw or the like said member 24 is secured to the rod 22 to move therewith.

25 Pivoted secured as at 26 within the lower end of the member 21 is one end of a lever 27 which operates in an elongated slot 28 provided 35 in the member 21. At its pivoted end the member 27 has secured thereto in any suitable manner, preferably by being integral therewith a foot pedal 29 which operates through a relatively short slot 30 provided in the lower end of the member 40 21 opposite to the slot 28.

30 At its free end lever 27 is operatively connected with the rod 22 through the medium of a link 31 pivoted at one end to the link 27 and at its relatively opposite end pivoted within the bifurcated 45 lower end of the rod 22 as at 32. It will thus be seen that pressing on the pedal 29 to move the same from the full line position to the dotted line position shown in Figure 1 lever 27 will be rocked, and the movement of the lever will, 40 through the medium of the link 31, be transmitted to rod 22 for moving the latter together with the member 24 from the full line position shown in Figure 1 to the dotted line position shown in said figure for elevating the garment hanger engaged 55

with the hook 23 and the garment on said elevator. Thus in this way is the garment on the hanger moved upwardly into a position adjacent to and in substantial alignment with the mouth of a bag 18.

With the parts in the dotted line position shown in Figure 1 the operator need only pull the uppermost bag 18 downwardly and over the garment while the same remains on the hanger suspended 10 from the hook 23.

From the above it will be seen that the bag 18 may be readily placed on the garment to cover the same.

When the bag has been placed over the garment 15 in the manner just described the garment and its hanger may be readily removed from the hook 23, the foot taken off the pedal 29, and rod 22 and associated parts will then by gravity return from the dotted line position to the full line position 20 shown in Figure 1. The device is now in readiness for the next operation incidental to the placing of a bag over the garment.

It will be understood that bags of suitable and 25 varying length may be placed on the rod 17 and when it is desired to make use of a bag of a desired size the operator may grasp any one of the handles 15 and revolve the arm assembly until the selected group of bags is brought in position whereby one of them may be used for covering a

garment in a manner hereinbefore described in detail.

Having thus described the invention, what is claimed is:

1. In a device of the character described, and in combination with means for suspending a garment bag or the like in elevated position, a fixed tubular member, a rod having a vertical sliding fit in said member, a hook on the upper end of said rod and adapted to have a garment hanger engaged therewith, a foot pedal pivotally mounted at the lower end of said tubular member, and link means operatively connecting said pedal with the rod for transmitting movement of the pedal to the rod for elevating the latter, and a cover sleeve 10 for said tubular member secured at one end to said rod for movement therewith.

2. In a device of the character described, a fixed perpendicularly disposed tubular member, a rod having a sliding fit in said member, a cover 20 sleeve for the tubular member secured at one end to said rod for movement therewith, a foot pedal pivotally mounted at the lower end of said tubular member, link means operatively connecting the pedal with the rod for transmitting movement of the pedal to the rod, and said tubular member being provided with a slot longitudinally elongated to accommodate said link means.

CHARLES F. WELLS.
WILLIAM O. PURKINS.
